UNITED STATES PATENT OFFICE.

JOHN R. CUMMINGS, OF CHICAGO, ILLINOIS, ASSIGNOR TO THE AMERICAN PRESS ASSOCIATION, OF SAME PLACE.

TYPE.

SPECIFICATION forming part of Letters Patent No. 337,744, dated March 9, 1886.

Application filed June 12, 1885. Serial No. 168,489. (No model.)

To all whom it may concern:

Be it known that I, JOHN R. CUMMINGS, a citizen of the United States, residing at Chicago, in the county of Cook and State of Illinois, have invented certain new and useful Improvements in Types; and I do hereby declare the following to be a full, clear, and exact description of the invention, such as will enable others skilled in the art to which it appertains to make and use the same.

My invention relates to an improvement in types to be used in electrotyping.

In the manufacture of electro - printing sheets it is necessary that the spaces and quads in the form from which the mold is taken should be shoulder high, and that they should be kept down and not allowed to come above the level of the shoulder of the type. As is well known, the wax, in being taken from the form, is liable to pull up the types, spaces, and quads. The types are easily planed down; but great labor and care are required to push down every space and quad. If they are allowed to remain up above the shoulder of the types, the shell will be to that extent shallower, and its under side uneven and lacking proper bearing - surface. Should a large number of molds have to be made from one form, the work of pushing down quads and spaces would not only be expensive, but would necessitate a waste of time on occasions when every moment would be of great importance, especially when making a large number of pages from news-matter.

To overcome the difficulty occasioned by spaces and quads pulling up in the form, I provide them with a rib on one side and a recess in the opposite side, and provide the shank of the type with a like recess on both sides, so that when the matter is in form the rib on the spaces and quads takes into the recess in the types, and the spaces and quads, when the form is locked up, are thereby prevented from pulling or working up.

My invention is clearly illustrated in the accompanying drawings, wherein Figure 1 represents a quad and also a space provided with a rib on one side and a recess on the

opposite side. Fig. 2 represents a type provided with a recess in both sides. Fig. 3 is a vertical section of a portion of a column of matter, showing how the spaces and quads interlock with the type.

I am aware of the patent to J. A. Wilkinson, No. 9,525, dated January 4, 1853, in which are shown tapering types, each of which has a rib on one side and a groove on the other to lock into each other and into corresponding ribs and grooves on the inside face of cylinder - heads of a printing-press. It is necessary in his arrangement of the types on the cylinder that he should provide means for interlocking the whole form, and accordingly he provides each and every letter, space, and quad with a rib and a recess. Now, if either one of these parts should be improperly placed in the form, damage would certainly result from locking up the form.

I am also aware of English patent to Crosse, No. 2,211 of 1855, in which are shown types provided with both a recess and a rib on each side. As these types are reversible—that is to say, have a printing-face on each end—they are designed to interlock when placed either end up; but should a type be placed in the form wrong side forward, its rib would abut against the rib on the adjoining type, precisely as would be the case with the Wilkinson type, above alluded to.

I lay no claim to what is shown and described in either of the above-mentioned patents.

My invention contemplates preventing the spaces and quads from pulling up, and to accomplish this I place the rib on those parts only, and by reason of the types being provided with a recess on both sides it is immaterial as to safety in locking the form whether or not the letters, spaces, or quads be set with "nicks turned," as frequently happens.

Having thus described my invention, what I claim as new, and desire to secure by Letters Patent, is—

A font of types the bodies of the letters of which are formed with a recess in two op-

posite sides, and the quads and spaces of which are provided with a rib on one side and a recess in the opposite side, the surfaces of those sides of the bodies of the types and 5 of the quads and spaces being otherwise plane, substantially as described, and for the purpose stated.

In testimony whereof I affix my signature in presence of two witnesses.

JOHN R. CUMMINGS.
